PENCIL

Eugene W. Knuth, Land O' Lakes, Wis.

Application December 13, 1933, Serial No. 702,133

6 Claims. (Cl. 120—83)

This invention relates to an improved pencil construction and more particularly to an improved construction for pencils of the type most commonly called "carpenters" pencils.

5 The main objects of the invention are to provide a pencil of the type referred to in which the lead or other writing material element is arranged in a manner which will facilitate the drawing of good lines or the like accurately along 10 a straight edge or other guiding edge; to provide an improved arrangement which can be easily and economically manufactured, and in general, it is the object of the invention to provide an 15 improved pencil construction of the type referred to.

Other objects and advantages of the invention will be understood by reference to the following specification and accompanying drawing, in which a pencil embodying a selected form of the 20 invention is illustrated.

In the drawing, Figs. 1 and 2 are edge and side views respectively of the pencil;

Fig. 3 is a cross section on the line 3—3 of Fig. 1;

25 Fig. 4 is a cross section similar to Fig. 3 but showing a modified arrangement; and

Figs. 5, 6 and 7 illustrate various situations in which the improved pencil construction may be 30 advantageously used.

Referring now to the drawing, the pencil construction shown in Figs. 1, 2 and 3 comprise an elongated body 10 which may conveniently be of wood or other suitable material, the body being 35 of relatively wide or thin rectangular cross section, as clearly shown in Fig. 3.

In one of the wide faces of the body 10, there is recessed a strip 11 of lead or other suitable writing material. As shown in Fig. 3, the lead 40 strip 11 may be of substantially square cross section, but it may be of rectangular or other cross-sectional shape. The lead is preferably recessed into one of the wide faces so that when the pencil is used, it may be placed with its wide lead-containing face against the straight edge, in which case the engagement of the wide pencil face will prevent turning of the pencil and thereby facilitate the accurate following of a straight edge or other guide member.

50 So as to readily distinguish the lead-containing side of the pencil from the opposite side, the corners of the opposite side are preferably beveled or otherwise treated, as indicated at 12, 12. The lead may be cemented in the groove 13 formed

in the body, or it may be dovetailed or otherwise keyed in the body, substantially as indicated in Fig. 4.

The body may be shaped otherwise than as shown in Fig. 3, but some more or less rectangular arrangement appears preferable. For example, as shown in Fig. 4, the lead-containing face of the body may be slightly rounded (convexly), while the opposite face may be flat or otherwise. The edge faces may be subjected to any desired treatment to give the pencil any distinctive cross section which may be desired.

It is preferable, however, that in any form of cross section, the arrangement be such that relatively large body portions be disposed on opposite sides of the embedded lead strip so as to afford adequate support for the lead against lateral thrusts. The rounded lead-containing face arrangement shown in Fig. 4 may be advantageous, especially where draftsmen use a long strip of commercial lumber for a straight edge, because the finish on such lumber is sometimes comparatively rough and the rounded face of the pencil will more readily slide over such a rough edge. The rounded lead-containing face 55 may also be desirable where the pencil is to be used in following concavely curved guiding edges.

As shown in Fig. 5, the described pencil construction may be advantageously used where it is desired to draw a guide line across various forms of mill work in which the face of the work is not a smooth plane but contains recesses or 60 valleys. As shown in Fig. 6, the described pencil construction is advantageously used for drawing a guide line across warped lumber. In Fig. 7, the pencil is advantageously used for drawing a guide line around one cylindrical object on the surface of another. It will be seen that because the lead is disposed at one side of the pencil, a vertical position of the pencil against the guiding member 65 will result in an accurately drawn guide line, even though the surface on which the line is drawn does not closely follow the guide member. Because of the absence of any angle from the writing point to that portion of the pencil which engages the guide member, there will be no variation in the location of the line drawn with respect to the edge of the guide member, even though the pencil moves up and down relative to the 70 guide element it being only important that the vertical position of the pencil be maintained.

Changes in the described structure may be made without departing from the spirit of the invention, the scope of which should be deter-

mined by reference to the following claims, the same being construed as broadly as possible consistent with the state of the art.

I claim:

5. 1. A pencil of the class described, comprising a body and a strip of writing material recessed into the body so that one face of the writing material strip is substantially flush with the corresponding face of the body, the writing material strip being of small cross sectional dimensions compared with those of the pencil and disposed wholly at one side of the pencil.
10. 2. A pencil of the class described, comprising a body and a strip of writing material recessed into the body so that one face of the writing material strip is substantially flush with the corresponding face of the body, the body being relatively wide but thin in cross section and the writing material strip being recessed substantially centrally into one of the wide faces of the body whereby the body portions on opposite sides of the strip afford adequate support for the strip when subjected to lateral thrust.
15. 3. A pencil of the class described, comprising a body and a strip of writing material recessed into the body so that one face of the writing material strip is substantially flush with the corresponding face of the body, the body being of relatively wide but thin, generally rectangular

30.

cross-section and having one of its wide walls substantially flat, the writing material strip being recessed centrally into said flat face of the body whereby said flat face is adapted to engage a straight edge or the like to prevent turning of the pencil.

35. 4. A pencil of the class described, comprising a wood body having a substantially flat face and a strip of lead having a substantially flat side, the lead strip being recessed into one side of the body so that said flat side is substantially flush with the flat face of the body, the lead strip being of small cross-sectional dimensions compared with those of the body and disposed wholly at one side of the latter.

85. 5. A pencil of the class described, comprising a wood body of relatively wide but thin, generally rectangular cross-section, and a lead strip also of rectangular cross section, said lead strip being recessed into one of the wide faces of the body so as to position the outer face of the lead strip substantially flush with the face of the body.

90. 6. A pencil of the class described, comprising a body having one face only slightly convexly curved, and a lead strip recessed into said curved face of the pencil and having a face portion substantially flush with said curved face of the body.
